CLAIM

The ornamental design for table and seating arrangement, as shown and described.

DESCRIPTION

FIG. 1 shows a perspective view of a first embodiment of a table and seating arrangement according to the principles of the present invention;

FIG. 2 shows a front elevational view thereof, a rear elevational view not being shown as it is a mirror image of the front elevational view;

FIG. 3 shows a right side elevational view thereof, a left side elevational view not being shown as it is a mirror image of the right side elevational view;

FIG. 4 shows a top plan view thereof;

FIG. 5 shows a perspective view of a second embodiment of a table and seating arrangement according to the principles of the present invention;

FIG. 6 shows a front elevational view thereof, a rear elevational view not being shown as it is a mirror image of the front elevational view;

FIG. 7 shows a right side elevational view thereof, a left side elevational view not being shown as it is a mirror image of the right side elevational view; and,

FIG. 8 shows a top plan view thereof.
